ATTORNEY.

UNITED STATES PATENT OFFICE.

MICHAEL BONSIAKOS, OF SAN FRANCISCO, CALIFORNIA.

MARKING DEVICE.

1,367,939.

Specification of Letters Patent.

Patented Feb. 8, 1921.

Application filed September 7, 1920. Serial No. 408,476.

To all whom it may concern:

Be it known that I, MICHAEL BONSIAKOS, citizen of the United States, residing at San Francisco, in the county of San Francisco and State of California, have invented a new and useful Improvement in Marking Devices, of which the following is a specification.

This invention relates to a marking device.

It is the principal object of the present invention to provide a marking device which is cheap and inexpensive in construction and may be readily adjusted to permit a wide range of characters to be fixed on a desired surface. The invention contemplates the use of a form within which a plurality of type belts are mounted and positioned around small selectively revoluble gears, said gears being easily set to disclose the desired character in a position for marking.

The invention is illustrated by way of example in the accompanying drawings, in which:

Figure 1 is an enlarged view in section through the marking device, as seen on line 1—1 of Fig. 2.

Fig. 2 is a view in perspective of the device.

Fig. 3 is a fragmentary view drawn on a reduced scale and showing one of the operating gears and the manner in which it engages the type band.

Referring more particularly to the drawings: 10 and 11 indicate side frame members of the stamping device, which members are held together by a U-shaped metal plate 12, this plate extending along the opposite sides of the members and across one end thereof, thus allowing the opposite end to be opened as indicated at 13 in Fig. 2.

The side members 10 and 11 may be satisfactorily formed of wood and will thus provide bearings for a plurality of shafts 14 and 15. The shaft 14 is secured across the compartment formed within the structure and near the opened end thereof. This shaft is preferably provided with bearings 16, upon which are mounted a plurality of freely revoluble gear disks 17. The shafts 15 which extend through the side walls 10 and 11 are arranged in parallel spaced relation to each other and the shaft 14. These last named shafts may be of any desired

number and are provided to rotate gear disks 18 and 19.

The disks 19 are preferably keyed to the shafts while the disks 18 are mounted for rotation thereon and are formed with extension hubs 20 which project through the side walls 11, at the same time providing a bearing for the shafts. It will be noted that the combined number of gears 18 and 19 agree with the combined number of gears 17 mounted on the shaft 14, and that the various sets of gears 18 and 19 are in transverse alinement with the complementary gears 17. This will provide suitable support for type bands 21. These bands are continuous and are preferably formed as indicated in Fig. 3, where it will be seen that their inner faces carry a plurality of serrations adapted to register with projecting teeth 22 on the gear disks 17, 18 and 19. The outer faces of these bands carry type 23. In some instances these type represent the letters of the alphabet and in others numerals. This may be determined as desired, although for the purpose of the present description it is preferable to have the outermost type bands carrying letters of the alphabet and the intermediate bands carrying numerals. In this connection it will be also noted that the bands are of different lengths, graduating toward the center.

Movement of the bands to bring a desired one of the type in register with the opening 13 is brought about by the index members 24, which are secured in one instance to the ends of the shafts 15 and in the other to the extension hubs 20 of the gears 18. The characters represented by the type are indicated on the faces of the members 10 and 11, so that the fingers of the members 24 may be readily adjusted to register with any one of the characters selected, this movement having a direct bearing upon the movement of the type bands and insuring that a corresponding character will be brought to register with the opening 13 in the end of the frame.

In operation of the present invention, the structure is assembled as shown in the drawings, and by rotating the various index members 24 the disks 18 and 19 will be adjusted and will positively move the type bands 21 to cause a series of type characters to register in the opening 13. The characters may then be inked or otherwise prepared

for marking and may then be impressed upon a plain surface.

It will thus be seen that the invention here disclosed is quite simple in its construction and operation and provides a compact marking device by which a wide range of characters may be supplied and conveniently impressed upon the article to be marked.

While I have shown the preferred form 10 of my invention as now known to me, it will be understood that various changes in the combination, construction and arrangement of parts may be made by those skilled in the art, without departing from the spirit of the 15 invention as claimed.

Having thus described my invention, what I claim and desire to secure by Letters Patent is:

1. The combination in a marking device 20 of a frame work open at one end and closed at the opposite end, a series of transverse shafts having hubs journaled successively from the closed toward the open end, and with gear disk mounted upon the shafts, a 25 single shaft fixed in the frame contiguous to the open end, gear disks journaled on said shaft in planes corresponding with the first named disks, endless type bands extending around the coöoperating upper and lower 30 disks, said bands being of decreasing lengths from the outermost disks to the innermost disks, and means for independently turning the upper shaft hubs, and advancing the type bands.

2. The combination in a marking device 35 of a frame work open at one end with transverse shafts having hubs journaled suc-

sively therein between the open and the closed end of the frame, toothed disks fixed upon the shafts, a shaft fixed within the frame 40 contiguous to its open end, with toothed disks turnable freely on the shaft, and in planes with the first named disks, endless type belts movable around the alined pairs of disks, index fingers fixed to the outer 45 ends of the turnable shaft hubs, and corresponding characters on the exterior of the frame, and which the fingers are movable to indicate corresponding type on the belts.

3. In a device of the character described, 50 a frame structure having a printing opening at one end, a fixed shaft carried by the frame adjacent said opening, a plurality of disks freely revoluble upon said shaft, a plurality of revoluble shafts carried by the 55 frame in spaced paralleled relation to each other and the fixed shaft, a disk keyed on each of said shafts and disposed in the same plane with a disk on the fixed shaft, means for selectively rotating said shafts, endless 60 type carrying belts disposed around the pairs of alined disks and other disks carried by the revoluble shafts and disposed in planes with disks on the fixed shaft, and means for rotating said last named disks independently of the shafts.

In testimony whereof I have hereunto set my hand in the presence of two subscribing witnesses.

MICHAEL BONSIAKOS.
